UNITED STATES PATENT OFFICE.

EDWARD D. MACKINTOSH, OF BROOKLYN, ASSIGNOR TO PAUL PRYIBIL,
OF NEW YORK, N. Y.

MACHINE FOR MAKING COMPRESSED BUNGS.

SPECIFICATION forming part of Letters Patent No. 336,652, dated February 23, 1886.

Application filed December 12, 1885. Serial No. 185,505. (No model.)

To all whom it may concern:

Be it known that I, EDWARD D. MACKINTOSH, of the city of Brooklyn, in the county of Kings and State of New York, have invented a new and useful Improvement in Machines for Making Compressed Bungs, of which the following is a specification.

My invention relates more particularly to machines for making bungs in which the grain of the wood extends transversely to the axis of the bung.

In making such bungs with my machine a stick of wood is first sawed by a series or gang of saws into square blocks of about the thickness required for a bung. Such blocks are then fed through a suitable chute, whereby they are caused to descend, one after another, upon a rest or table in front of a tubular knife or cutter, and are then, by a reciprocating plunger, forced against and passed through the knife or cutter, after which the round blanks descend into a second chute and into a blank-holder, and are, by the action of a reciprocating compressing-die acting in connection with a fixed die, compressed to give them the taper form desired.

In this machine it is necessary to provide against any accident by reason of the bungs not being fed properly through the successive stages of the operation, and to guard against any derangement or breakage of the parts of the machine by reason of the bung-blanks being of a thickness greater or less than that usual, and also to provide for readily adjusting the parts of the machine to suit bung-blanks of different sizes.

My invention consists in a novel construction of the female compressing-die, which enables it to lift or move aside any bung-blanks which are unduly projected through the feeding-chute for round blanks, and in the combination, with such peculiar female compressing-die, of a male compressing-die and a reciprocating or yielding basket or holder, into which the blanks are delivered to be acted upon by such dies.

The invention also consists in a novel combination of parts, whereby the table or rest, which is supported at the lower end of the chute for square blanks, may be adjusted so as to bring the center of the square blank,

whatever be its size, always opposite the axis of the tubular knife which is to cut it into circular form.

The invention also consists in a novel combination of parts, whereby the fronts of the chutes for square and round blanks, which are supported so as to be free to move outward, either by swinging or otherwise, are caused to act upon a tripping mechanism, and thereby to throw off or release the driving-clutch through which the machine is operated.

The invention also consists in other combinations of parts, which are hereinafter described, and pointed out in the claims.

In the accompanying drawings, Figure 1 is a sectional elevation of a machine illustrating my invention. Fig. 2 is a plan thereof. Fig. 3 is a transverse vertical section upon the 70° plane of the dotted line *x x*, Fig. 1, looking toward the right hand of Fig. 1. Fig. 4 is a transverse section upon the same plane, looking toward the left hand of Fig. 1. Fig. 5 is a vertical section, upon a larger scale, illustrating the tubular knife and compressing-dies and portions of a chute through which the round blanks are delivered from the knife to a yielding basket or blank-receiver operating in conjunction with said dies. Fig. 6 is an 80° end view of the blank receiver or basket and the male compressing-die. Fig. 7 is an end view of the female compressing-die. Fig. 8 is a horizontal section upon the plane of the dotted line *y y*, Fig. 5, through the male compressing-die and the yielding blank receiver or basket, and a plan of the female compressing-die. Fig. 9 is an elevation of the lower portion of two side pieces which compose the chute for square blanks, the table or rest at 90° the lower end of such chute, and a hanger whereby it is supported. Fig. 10 is an elevation at right angles to Fig. 9 of the parts shown therein; and Figs. 11 and 12 are respectively an end view and a side view of a 95 sleeve and a locking and tripping lever which are comprised in the tripping mechanism of the machine. Figs. 5 to 12, inclusive, are upon a larger scale than Figs. 1, 2, 3, and 4.

Similar letters of reference designate corresponding parts in all the figures.

A designates a saw-arbor, which is supported

by suitable bearings, a a' , and on which are a series of saws, a^2 , supported and held at suitable distances apart by collars a^3 . The saw-arbor and saws are to be driven by a belt running upon a pulley, a^4 .

For cutting up sticks to produce bung-blanks of different sizes the saws should be set at different distances apart, and provision is afforded for removing them from their arbor by 10 first removing the outermost bearing, a' , which fits in a dovetailed slideway, a^5 , in the upper part of the frame.

Adjacent to the gang of saws a^2 is arranged a trough or stick-holder, B , which is mounted 15 upon arms b , projecting upward from a rock-shaft, b' , which is supported in standards b^2 , projecting from the main frame C of the machine. The trough or channel B is notched at b^3 to receive the saws a^2 ; but when the gang of saws 20 is differently arranged it is necessary to provide a channel or trough, B , having notches b^3 correspondingly arranged.

In order to provide for removing the trough B , and readily replacing it by another of different size, I construct it with dovetailed projections b^4 upon its bottom, which enter dovetailed slideways in the upper ends of the arms b , as best shown in Figs. 1 and 3. The trough or channel B has at the side a handle, b^5 , 30 whereby it may be swung backward and forward upon the rock-shaft b' , in order to present the stick within it to the saws a^2 . From a point coincident with the inner end of the channel or trough B , when swung backward 35 away from the saws, there extends a chute for square blanks, which consists of two side pieces, D , having upon their inner faces flanges d , which project toward each other and prevent the blanks from escaping from the chute. 40 This chute is curved from a horizontal position at the upper end into a vertical position at the lower end, as best shown in Fig. 1. The upper ends of the side pieces, D , are provided with hubs or eyes d' , which fit a horizontal stud or projection, d^2 , extending from the side of one of the bearings a , and by set-screws d^3 the pieces D may be secured at the desired distance apart upon such stud or projection. At their lower ends the side pieces, 45 D , of the chute are attached to blocks or slides D' , which have at their back dovetailed projections d^4 , fitting a correspondingly dovetailed slideway, d^5 , in a part of the framing C , and which may be adjusted toward and 50 from each other by means of a rod or shaft, d^6 , having upon it right and left hand threads fitting corresponding nuts in the blocks D' , as best shown in Fig. 9. The screw d^6 is provided with a hand-wheel, d^7 , whereby it may 55 be turned, and is held against longitudinal movement by the bearing d^8 in the frame of the machine, as shown in Figs. 2 and 3. At its inner end one side of the channel or trough B is provided with an inward projection or 60 shoulder, b^6 , as best shown in Fig. 2, which forms a stop to limit the inward movement of a stick inserted into the trough B . At its ad-

jacent end one of the side pieces D of the chute is provided with an inclined lip or projection, b^7 , which is also shown in Fig. 2, and the trough 70 B is notched at b^8 to enable it to pass this finger or projection b^7 . The finger or projection b^7 forms an incline, which covers the projection b^6 when the trough B is brought back to the position shown in Fig. 2, and at its opposite side the inner wall of the trough B is 75 flared outward, as shown at b^9 .

In using the machine a stick of wood of proper size is thrust into the trough B until its end strikes the lip or projection b^6 , when 80 it cannot go any farther, and the trough is then swung toward the saws to cut the stick into a number of blanks corresponding to the number of saws. The trough is then swung back to the position shown in Fig. 2, and as 85 the incline b^7 enters the trough it cant or tilts the first blank sidewise and out of engagement with the shoulder b^6 . The blank being short the flare or enlargement b^9 at the opposite side of the trough enables it to tilt or assume such 90 inclined position, and as the next stick is thrust into the trough the blanks will all be shoved from the trough between the side pieces, D , of the chute, each of the blanks as it reaches the incline b^7 being deflected sidewise, so as to pass the shoulder b^6 . The arms b may have toes b^* , which, by striking against the frame, as shown in Fig. 3, form stops to limit the swinging movement of the trough away from the saws. Adjacent to the lower 100 end of the chute D for square blanks is a tubular knife, E , the axis of which is horizontal, and which has at the end cutting-projections, which give the knife the common name of a "fish-mouth" knife. This knife is 105 best shown in Fig. 5. It is held within a socket, e , and above and below it are auxiliary cutters e' , which are held in place by set-screws e^2 , and insure the division and consequent falling of the chips produced by the 110 knife E , and prevent the machine from becoming clogged with chips. The inner end of the knife E rests against a shoulder, e^3 , in the socket e , and at the upper side of the socket is a spring-retainer, e^4 , which bears up 115 on the top of the blanks S , and serves to properly regulate their exit from the knife into a chute, F , which descends from the exit-opening of the knife and socket. As the blanks descend in the chute D , they are 120 brought one by one upon the table or rest G , which remains immediately below the chute, and about in line with the bottom of the knife E .

H designates a ram or plunger, which is 125 fitted to suitable bearings, c , in the frame C , and is operated by a connecting-rod, H' , from a crank-shaft, H^2 , which is itself supported in suitable bearings, c' , in the frame of the machine. On the ram H is an upward projection, e^5 , in which is secured by a set-screw, e^6 , a plunger, e^7 , made slightly smaller than the interior of the knife E , and arranged in line axially therewith. The ram H advances period-

ically, and the plunger e^1 forces the blank which has fallen to the table or rest G against the knife E , and thereby causes the knife to cut the blank into circular form. The blanks are by the 5 plunger e^1 pushed ahead and into the knife one by one, and during the operation of the machine the knife is filled with blanks S , as shown in Fig. 5. The spring e^4 (shown in Fig. 5) produces a dragging action upon the top of 10 the blank S as it passes beneath it, and holds the upper edge of the blank back, so that the blank will usually become detached from the socket-piece e at its lower edge, as is illustrated by dotted lines in Fig. 5, and will fall edgewise, 15 and in proper position into and through the chute F . The blank will, by the spring or retainer e^4 , be prevented from tilting over, and thus entering the larger or upper end of the chute F flatwise, which would clog the chute.

20 In order to operate upon bung-blanks of different sizes, for producing different-sized bungs, it is necessary that the side pieces, D , of the chute for square blanks, should be moved more or less toward and from each 25 other, as the case may be, and it is necessary that the table or rest G should be correspondingly raised or lowered, so that the table or rest will always hold the bung-blank, whatever be its size, with its center opposite the 30 axis of the knife E . To provide for this adjustment of the table or rest G , I connect the blocks or slides D' , which may be considered as the lower ends of the side pieces, D , of the chute, by an angular hanger, G' , which in its 35 lower angle supports the table or rest G . The two arms of this angular hanger fit grooves f in the blocks D' , and are secured therein by bolts f' , passing through slots f'' in the hanger. The hanger is thereby given a sliding bearing 40 in the blocks D' , and as said blocks and the side pieces, D , of which they form part, are adjusted toward or from each other the hanger and the table or rest G , which it supports, will be correspondingly raised or lowered.

45 The two portions or members of the hanger G' may be considered as forming arms or bearings, which are inclined at opposite angles from the side pieces, D D' , and which support the table or rest G .

50 In order to enable the table G to be properly adjusted when the machine is first erected, I have represented it as supported and held by a clamping-screw, f^2 , passing through the hanger and entering the table, and by a set-screw, f^3 , as shown in Fig. 9. By setting up the set-screw f^3 the table or rest will then be moved upward along the opposite side of the hanger to the required position, and then there held by tightening the clamping-screw 55 f^2 . The table or rest G having been thus properly adjusted relatively to the other parts of the machine, will be automatically raised and lowered with the hanger whenever the side pieces, D , are adjusted toward 60 and from each other. As best shown in Fig. 1, the table or rest G has at one side a flange, J^4 , which laps downward on the face of the

hanger G' . As the circular blank drops down the chute F for round blanks, it falls into a blank receiver or basket, g , which is a semi-circular projection upon the end of the collar g' , adapted to slide upon the exterior of the male compressing-die I , and in the end of the ram H is fixed a cup shaped or female compressing-die, I' . (Best shown in Figs. 1, 5, and 7.) The male compressing-die I is, as here represented, held in place by a bolt, I^2 , inserted through the framing C of the machine and screwed into the die, and, as shown in Fig. 1, this bolt is hollow, and has arranged within it 70 a sliding rod, g^2 , which is surrounded by a spring, g^3 , tending to constantly press it forward or toward the female compressing-die I' . The blank receiver or basket g has in its lower side an upwardly-projecting pin or screw, g^4 , 75 which works in the slot g^5 in the male compressing-die I , and against which the end or head of the spring actuated rod g^2 bears. By means of this spring-actuated rod or head the blank receiver or basket is automatically projected into the position shown in Figs. 1 and 5, so as to catch the bung-blank S , which drops through the chute F , and when the female compressing-die I' advances the receiver or basket g g' will, by the resilience of the spring 95 g^3 , yield to the pressure of the female compressing-die, and be pushed backward on the male die out of the way, leaving the blank caught between the male and female compressing-dies.

100 In order to prevent the blank when it falls onto the receiver or basket g g' from tilting forward, I have shown the latter as provided on opposite sides with spring-retainers g^6 , which are arranged in grooves g^7 within the receiver or basket, and which are slightly hooked or turned inward at their outer ends, as shown in Fig. 8. As the blank falls, it drops behind the hooked ends of the spring-retainers g^6 , and is thereby prevented from tilting forward, and when the yielding receiver or basket g g' is pushed back by the female compressing-die the spring-retainers g^6 will yield outward, so as to enable them to readily pass the blank.

110 Arranged axially within the female compressing-die is a stationary rod or ejector, I^3 , which, as here shown, is fixed by a pin or screw, g^8 , to a part of the framing C . The ram H is slotted at g^9 on its under side to pass the pin g^8 , and is bored out to receive the 115 ejector I^3 within it. As the female compressing die I' is advanced by the movement of the ram H , it leaves the ejector I^3 behind it, and by the action of the dies I I' the circular bung-blank is forced into the taper cup-shaped compressing-die I' , and is thereby compressed and given the desired taper form. As the female compressing-die I' recedes, it has the completed bung within it, and before it completes its return movement the bung is brought against 120 the end of the stationary ejector I^3 and pushed out of the cup shaped compressing-die I' , falling into a box or basket placed to receive it. 125 In the ordinary operation of the machine it

is intended that but one blank S at a time shall leave the inner end of the knife E and fall through the chute F into the blank receiver or basket g, and but one blank will fall 5 in case the blanks are of uniform thickness. It will be readily seen, however, that if a blank which is somewhat thinner than the others is entered into the knife E the blank which is at the inner or delivery end of the throat or 10 socket e will not fall, and the operation of the machine will continue, except that at the next forward movement of the ram H the compressing-die I' will not receive any blank, and will return empty. If it further happens that 15 a thick blank be forced into the knife E at the next forward movement of the ram H, two bung-blanks will be delivered, one after the other, into the chute, and the upper one will rest upon the lower one, which latter is supported by the blank receiver or basket g. If 20 this second or upper blank should be thus brought unduly within the range of the female compressing-die I', the die would force the second blank also forward, and would push 25 forward or swing outward the movable front F' of the chute F, which is more fully herein-after described. In order to prevent this, I form upon the top of the female compressing-die an inclined or wedge-like surface, g¹⁰, 30 which is best shown in Figs. 5 and 7. When thus constructed, the female compressing-die will, if a second or upper blank be in its way, pass under said blank, and the inclined surface g¹⁰ will lift the upper blank and enable 35 the die to act with compressing or crushing force only on the single blank which is within the basket or receiver.

Near the lower ends of the side pieces, D, which constitute the chute for square blanks, 40 the flanges d at the front thereof are removed, and the plate D², which constitutes the front of such chute, is secured by a set-screw, h, to an arm, D³, which is mounted upon a rock-shaft, h'. Upon the same rock-shaft h', but 45 capable of swinging independently of the arm D³, is a lever, D⁴, and that portion of the arm D³ which projects above the rock-shaft has a lateral projection or ear, h², which is adapted to bear against a set-screw, h³, carried by the 50 lever D⁴, and capable of adjustment therein. The front plate, F', of the chute F is also mounted upon a rock-shaft, F², so that it may swing outward, the rock-shaft being supported in suitable bearings, c², projecting from the 55 framing C of the machine, as shown best in Figs. 2 and 4. The rock-shaft F² has at the end a downwardly-projecting arm, h⁴, which, as shown in Figs. 1 and 2, is connected by a chain or other connection, h⁵, with the lower 60 end of the lever D⁴.

From the above description it will be clearly understood that in case either of the chutes becomes clogged in any way, so as to oppose an obstruction in the way of the cutting 65 plunger or presser e' or the female compressing-die I', such obstruction will cause the front plate D² or F' of the chute to swing out-

ward. Such outward movement of the plate D² of the chute D for square blanks will cause the upper end of the arm D³ to act upon and move the lever D⁴, and such outward movement of the front plate, F', of the chute for round blanks will exert a pull through the chain h⁵, and will move the lever D⁴ in the same direction. The connection h⁵ between 70 the arm h⁴ and the lever D⁴ should be of such nature as to act by tensile strain only, and hence while such connection will transmit the swinging movement of the front plate, F', to the lever D⁴ it will not transmit any movement from said lever to the front plate, F', when the lever is moved by the swinging outward of the front plate, D², of the chute for 75 square blanks.

Upon the crank-shaft H² is a driving-pulley, 80 H³, which, through a clutch of suitable construction, transmits motion to the shaft. There are many different forms of clutch which comprise projecting arms or toes i, as shown in Fig. 2, and a spool or sleeve, i', adapted to 85 slide on the shaft and having a taper end, which, entering between the arms or toes i, forces them apart and makes the clutch operative to turn the shaft.

In carrying out my invention I employ a 90 tripping mechanism, whereby the clutch is held in operative position on the shaft, and which, when operated, will release the clutch from the shaft; and I employ connections 95 through which the movement of the lever D⁴ 100 serves to throw off the tripping mechanism and release the clutch.

In the machine which I have chosen to illustrate my invention the clutch spool or sleeve i' is controlled by a yoked lever, J, embracing the spool or sleeve, and fulcrumed at its lower end, j, as shown in Fig. 3. With the upper end of the lever J is connected a rod, J', which slides through a sleeve, J², as shown 105 in Figs. 1 and 2.

J³ designates a shifting or starting handle, which is fulcrumed at j', and has an upwardly-projecting forked arm, j², embracing the sleeve J², and connected therewith. In the sleeve J², which is best shown in Figs. 11 and 12, is fulcrumed at j³ a locking and tripping lever, J⁴, which, by means of a coil-spring, j⁴, applied to the fulcrum-pin of the lever, is held within a notch, j⁵, in the sleeve, and caused to project partly into the bore of the sleeve, as shown 115 best in Fig. 11. This locking and tripping lever J⁴, as it projects into the bore of the sleeve, enters a notch, j⁶, in the clutch-operating rod, J', and thereby holds the sleeve and rod against longitudinal movement, one relatively to the other. If the locking-lever J⁴ be engaged with the notch in the rod J', the starting-handle will when moved downward 120 move the sleeve J² and rod J' in a direction to force the spool or sleeve i' between the clutch arms or toes i, and will thereby lock the driving-pulley H³ to the shaft. The framing C of 125 the machine may itself form a stop to the lever J³ as the latter is moved downward.

I have in the drawings shown the lever J^3 , the sleeve J^2 , and the remaining parts of the clutch-operating mechanism in their middle or intermediate position, and by raising the lever J^3 upward the clutch will be naturally thrown off, while by moving it downward the clutch will be made fully operative.

Upon the rod J' , I have represented a spring, j^7 , acting between a shoulder on the rod and the end of the sleeve J^2 , and it will be readily understood that if the locking and tripping lever J^4 be pushed outward, so as to free it from the notch J^6 in the rod J' , the spring j^7 will throw the rod and the attached spool or sleeve i' in a direction to free the driving-pulley from the shaft, and the machine will be stopped.

The above-described lever D^4 is connected at its upper end with the rod D^5 , fitted to a guide, c^6 , and carrying at its end a knocking-plate, D^6 , having a considerable horizontal projection, as shown best in Fig. 2. Whatever be the position of the sleeve J^2 upon the rod J' , the plate D^6 will always have some portion of it opposite the lever J^4 , and if at any time the front plates D^2 or F' of the two chutes are swung outward by any obstruction they will act through the lever D^4 , rod D^5 , and plate D^6 , to throw the locking and tripping lever J^4 out of engagement with the notch in the rod J' , and the rod, being thereby released from the sleeve J^2 , will throw off the clutch and stop the machine.

In starting the machine it is only necessary, by means of the handle or lever J^3 , to move the sleeve J^2 until the locking and tripping lever J^4 engages the notch in the rod J' , and the handle or lever J^3 may then be operated to throw on the clutch and start the machine.

What I claim as my invention, and desire to secure by Letters Patent, is—

1. In a bung-making machine, the combination, with a male die and a yielding receiver for holding a bung-blank in front thereof, of a chute for delivering bung-blanks to the receiver, and a reciprocating female compressing-die having an inclined or wedge-shaped cam-surface which will lift or move aside any blank unduly obtruded in the path of said compressing-die, substantially as herein described.

2. The combination, with the male die I and spring-actuated yielding receiver g , of the chute F for delivering blanks to the receiver g , the reciprocating female compressing-die I' , having an inclined cam-surface, g^{10} , and the stationary ejector I^3 , substantially as herein described.

3. The combination, with the male die I and the spring-actuated yielding receiver g , having at opposite sides grooves g^7 and retaining-springs g^8 , of the chute F for delivering blanks to the receiver, and the reciprocating female compressing-die I' , having an inclined cam-surface, g^{10} , for lifting or moving aside blanks unduly obtruded in its path, substantially as herein described.

4. In a bung-making machine, the combination, with a chute for square blanks, composed of parallel side pieces, and a screw for adjusting them toward and from each other, of a table or blank-rest below the chute, and arms or bearers inclined at opposite angles from the side pieces and supporting the table or rest, whereby the table or rest will be raised when the side pieces are moved toward each other, and lowered when the side pieces are moved away from each other, substantially as herein described.

5. In a bung-making machine, the combination, with a chute for square blanks, composed of two side pieces adjustable toward and from each other, of an angular hanger forming a blank-support extending between the side pieces of their lower ends, and having sliding bearings in the side pieces, whereby the hanger will be raised and lowered as the side pieces are adjusted toward or from each other, substantially as herein described.

6. The combination, with a chute for square blanks, composed of two sides adjustable toward and from each other, of an angular hanger forming a blank-support extending between the side pieces at their lower ends, and having sliding bearings in the side pieces, whereby the hanger will be automatically raised and lowered as the side pieces are moved toward or from each other, and a blank table or rest adjustable upward and downward in the hanger, substantially as herein described.

7. The combination, with the chute for square blanks, having the side pieces, D , and the slides or blocks D' , to which said side pieces are attached, and which are slotted obliquely at f , of the screw d^8 , for adjusting the slides and attached side pieces, and the angular hanger G' , forming a blank-support and fitting the grooves f , and bolts f' passing through slots and holding it in said grooves, substantially as herein described.

8. The combination, with a chute for square blanks composed of side pieces adjustable toward and from each other, of the angular hanger G' , having sliding bearings in the side pieces, and connecting them and the triangular blank table or rest fitting the hanger, and held and supported on one side by a binding or clamping screw, f^2 , and on the other side by a set-screw, f^3 , substantially as herein described.

9. The combination, with chutes for square and round blanks, having movable front plates, of a clutch through which the machine is driven, a tripping mechanism whereby the clutch is held in operative position, a lever on which the movable front of one chute acts when moved outward, a connection between the movable front of the other chute and the lever, which operates only by tensile force, and a rod connected with the lever, and which serves to throw off the tripping mechanism and release the clutch, substantially as herein described.

10. The combination, with the chute for

square blanks, having a swinging front, D², and an upwardly-projecting arm, D³, of a clutch through which the machine is driven, tripping mechanism whereby the clutch is held in operative position, a lever, D⁴, on which the arm D³ acts when the front D² is swung outward, and a rod, D⁵, connected with said lever and serving to throw off the tripping mechanism, substantially as herein described.

10 11. The combination, with the chutes D F for square and round blanks, having movable fronts D² F', provided, respectively, with arms D³ h⁴, of a clutch whereby the machine is operated, tripping mechanism for holding the 15 clutch in operative position, the lever D⁴ on which the arm D³ acts, and which is connected with the arm h⁴, and a rod, D⁵, through which the lever acts to throw off the tripping mechanism when moved by the swinging outward 20 movement of either of the movable chute-fronts, substantially as herein described.

12. The combination, with a chute having a movable front, of a clutch through which the machine is driven, a rod for shifting the clutch, 25 a sleeve on the rod, and a locking and tripping lever pivoted in the sleeve and engaging a notch in the rod, and a rod receiving a longitudinal movement from the movable chute-front, and serving to throw out the locking and 30 tripping lever from engagement with the notch in the clutch-shifting rod when the chute-front is moved outward, substantially as herein described.

13. The combination, with a chute having a 35 movable front, of a clutch through which the

machine is driven, a notched clutch-shifting rod, a sleeve on the rod, and a locking and tripping lever fulcrumed in the sleeve and engaging the notch in said rod, and a rod receiving a longitudinal movement from the chute-front 40 when the latter is moved outward, and having at the end a broad plate, D⁶, for acting upon the locking and tripping lever, substantially as herein described.

14. The combination, with a chute having a 45 movable front, of the clutch and spring-actuated clutch-shifting rod J', the sleeve J², fitting on said rod and having the spring-actuated locking and tripping lever J⁴, fulcrumed to it and engaging a notch in the rod J', the starting-handle J³, connected with the sleeve J², and the rod D⁵, receiving longitudinal movement from the movable chute-front and serving to throw off the lever J⁴, substantially as 50 herein described.

15. The combination, with the chutes D F for square and round blanks, having movable fronts D² F', and arms D³ h⁴, of the lever D⁴ on which the arm D³ acts, and which is connected with the arm h⁴, the clutch-operating rod J', 60 the sleeve J², fitting on said rod and having the locking and tripping lever J⁴ fulcrumed in it, the starting-handle J³, connected with the sleeve J², and the rod D⁵, connected with the lever D⁴ and serving to throw off the lever J⁴, 65 substantially as herein described.

EDWARD D. MACKINTOSH.

FREDK. HAYNES.

Correction in Letters Patent No. 336,652.

It is hereby certified that in Letters Patent No. 336,652, granted February 23, 1886, upon the application of Edward D. Mackintosh, of Brooklyn, New York, for an improvement in "Machines for Making Compressed Bungs," an error appears in the printed specification requiring correction, as follows: In line 85, page 5, the word "of" should read *at*; and that the Letters Patent should be read with this correction therein to make it conform to the record of the case in the Patent Office.

Signed, countersigned, and sealed this 2d day of March, A. D. 1886.

[SEAL.]

H. L. MULDROW,
Acting Secretary of the Interior.

Countersigned:

M. V. MONTGOMERY,
Commissioner of Patents.
